UNITED STATES PATENT OFFICE.

ABRAHAM M. SOUTHARD, OF DENVER, COLORADO, ASSIGNOR TO THE
SOUTHARD PORTABLE GAS COMPANY, OF SAME PLACE.

APPARATUS FOR LIGHTING BUILDINGS.

SPECIFICATION forming part of Letters Patent No. 355,351, dated January 4, 1887.

Application filed March 30, 1886. Serial No. 197,141. (No model.)

To all whom it may concern:

Be it known that I, ABRAHAM M. SOUTHARD, of Denver, Arapahoe county, in the State of Colorado, have invented a certain new and useful Improvement in Apparatus for Lighting Buildings, of which the following is a specification.

I use stationary lamps burning Excelsior oil, a light product of the distillation of petroleum. My apparatus conduces to safety and convenience. I provide a sufficient tank within the top of the building, protected, as far as practicable, from the heat of the sun, to which I supply Excelsior oil at intervals, as required. This tank is connected by pipes with the several lamps, and the oil is let down to each by a valve, which may at will be tightly closed or be controlled automatically so as to let the oil down in the exact quantities required. A cock or other valve closed at will furnishes additional means for shutting off the oil. This latter means of excluding the fluid is particularly important when it is desired to examine or repair a lamp.

The following is a description of what I consider the best means of carrying out the invention.

The accompanying drawings form a part of this specification.

Figure 1 is a vertical section through a portion of a building having my invention. Fig. 2 is on a larger scale. It is a vertical section through a portion of one of the lamps.

Similar letters of reference indicate corresponding parts in both the figures where they occur.

A is the building; B, the tank; C, the pipes, properly branched and connected for leading the fluid to the several lamps under the pressure due to the difference of level between each lamp, respectively, and the reservoir.

D is a tight-fitting stop-cock, and E is the body of the lamp.

F are curved pipes, having smooth interiors, partly choked with a wicking tipped by burners G, which latter are considerably removed from and at a little height above the reservoir. There may be globes, shades, or other devices for shielding the flame and modifying the effect of the light.

A vertical tube, e, with both ends open, is fitted in the axial line of the body, its lower end being tightly soldered or otherwise joined to the bottom. Its upper end opens into the interior of the body near the top. H is an annular float, filling nearly the whole space between this tube and the interior of the body E. A tube, H', larger than tube e, extends upward from the inner edge of this float. H² is a hollow cone soldered or otherwise fixed on the top of H'. The apex of this cone matches in a corresponding conical recess or valve-seat at the junction of C with E.

A thumb-screw, K, tapped through the bottom, extends up and presses, or is capable of pressing, against the interior of the cone. When this screw is turned in one direction, it is forced up, and lifting the cone H² presses it tightly against its conical seat. This forbids the descent of oil so long as this condition obtains. The parts should be thus adjusted when they are to be for a long time disused.

When it is desired to operate one or more of the lamps, the corresponding screws, K, are turned in the direction to unscrew or sink the screws. This sets the cone H², and consequently the tube H' and float H, at liberty to rise and sink. If the surface of the oil in the body E is below the proper level, the float H and its connections will sink. This allows oil to descend from C into E. This raises the float H and closes the valve H². This constitutes an automatic regulation, the float H rising and closing or partially closing the valve whenever the level of the oil in the body E gets too high, and sinking and opening the valve and allowing more to descend whenever the surface of the oil in the body gets too low.

It may be understood that the gradual flow of the oil from the reservoir B to the burner is the same as is set forth in the patent to me dated December 29, 1885, No. 333,354; or I can use other devices and forms for utilizing the oil in the body. Devices for burning the oil in the vicinity of the reservoir B, but sufficiently removed therefrom to allow E and its contents to be kept cold, constitute an important part of my invention; but their forms may be varied within wide limits. It is only necessary that there be efficient means for utilizing the oil.

izing the oil kept at proper levels in the several lamp-bodies E E.

I attach importance to the fact that the automatic regulation due to the free rising and sinking of the float H and its connections will allow the oil to come down in just the proper quantities to supply the lamps when they are at liberty to move; and I also attach importance to the provision by the screw K for holding the valve and its connections tightly up into its seat, so as to exclude the oil entirely when desired. I also attach importance to the separate cock D, operated at will. Closing this allows me to safely unscrew the branches 15 or arms F, or the entire lamp E, at will. Beeswax or analogous material insoluble in Excelsior oil should, after each disconnection, be applied to the screw-threads, to insure a tight joint when the screw is again introduced.

Modifications may be made in the forms and proportions within wide limits without departing from the principle or sacrificing the advantages of the invention. I can use one alone of the bodies E instead of a series, as shown. I can have only one burner connected to each body instead of a number, as shown. The form of the body and of the burner and the relative sizes and lengths of the tubes may be varied within wide limits.

I am aware that oil-vessels have been supplied from a general reservoir, and that the oil-supply to burners has been controlled by float-valves arranged within said vessels. Such features I do not seek to cover in this application; but

What I claim as new is—

1. The combination, with the reservoir E, provided with the inlet and outlet openings, as shown and described, and tube e, arranged axially in said vessel, the float H, provided with the tube H', fitting over the tube e and having the valve H², of a screw-rod, K, arranged to operate the said valve independent of the float action, as set forth.

2. The combination, with the reservoir E, having inlet and outlets, as described, and having central vertical tube, e, of the float H, having tube H' and valve H², and the screw K, operating through the tube e, as and for the purpose set forth.

In testimony whereof I have hereunto set my hand, at New York city, this 4th day of March, 1886, in the presence of two subscribing witnesses.

ABRAHAM M. SOUTHARD.
